UNITED STATES PATENT OFFICE.

RALPH V. L. HARTLEY, OF EAST ORANGE, NEW JERSEY, ASSIGNOR TO WESTERN ELECTRIC COMPANY, INCORPORATED, OF NEW YORK, N. Y., A CORPORATION OF NEW YORK.

MULTIPLEX TELEGRAPHY.

Application filed March 9, 1922. Serial No. 542,250.

The present invention relates to the transmission and reception of telegraphic or similar signals by alternating currents or waves, the conversion from direct-current telegraph impulses to the alternating currents or vice versa being accomplished by commutation.

Telegraph transmission by means of alternating currents or waves, produced by any of the well-known wave generators and controlled in some manner as by a key or by direct-current impulses have been suggested, and the features of such a system have by this time become generally familiar. One of the principal advantages of such a system is that the same line may be used to transmit a number of currents of distinct frequencies which can be independently controlled by different signals and can be separately received by means of selective circuits, permitting of multiplex operation. The types of wave sources or generators heretofore devised and suitable for use in such a system are all relatively costly apparatus, and the use, particularly of vacuum discharge tubes which has become quite general in such systems, introduces certain difficulties in transmission which will be referred to more in detail hereinafter.

One object of the invention is to provide means and method, involving current commutation as stated, for securing the advantages of alternating current, or carrier current as it is commonly called, transmission at less cost of equipment than has been involved in systems heretofore devised.

A further object of the invention is to overcome the difficulties experienced in using discharge tubes, as mentioned above, the particular features for overcoming these difficulties to be explained in the detailed description to follow.

The use of commutators for transmission and reception in the manner to be described hereinafter requires that distantly separated commutators be synchronized. It is common to employ synchronized rotary distributors or the like in printing telegraph systems. These systems, even though they may operate four one-way or four two-way printing telegraph channels do not make use of more than a small portion of the total frequency range which the line is generally capable of transmitting, and it is a further object of the invention to utilize the range of frequencies heretofore left unused by a

printing telegraph system by providing a plurality of carrier telegraph channels operating in such range and to utilize the synchronizing apparatus of the printing telegraph system for the various commutators employed by the carrier channels.

Further objects and features of the invention will appear from the following detailed description of a typical embodiment of the invention as illustrated in the accompanying drawing, in which Fig. 1 shows a terminal station of a system embodying the invention; Fig. 2 shows a somewhat different arrangement of the circuits at a terminal station; and Fig. 3 shows a modification of a channel termination.

Fig. 1 shows a terminal station for the line ML, it being assumed that the opposite terminal is arranged identically with the one shown, or differs therefrom only in unessential respects. The line ML is in the present instance composed so as to serve for the transmission both of telegraphic impulses and alternating currents having frequencies higher than the frequencies involved in the telegraph impulses. The telegraph impulses in the present instance are those employed by the printing telegraph apparatus PT and a corresponding apparatus at the opposite terminal. The alternating currents are employed for repeating between the direct current telegraph line LL¹, LL² and similar distant lines by way of the main line ML. The printing telegraph impulses are separated at the terminal from the alternating currents or waves as a whole by the wave filters LP and HP.

These filters may be designed in accordance with the principles disclosed in the patent to G. A. Campbell, No. 1,227,113, issued May 22, 1917. The filter LP is a low pass filter and is designed to transmit freely all frequencies from zero to a predetermined upper limiting frequency, but to suppress the transmission of currents having frequencies higher than this limiting frequency. The high pass filter HP is designed to prevent the transmission of currents of the range of frequencies transmitted by the filter LP, but freely transmits frequencies higher than this range. A balancing network N is provided for matching the characteristics of the line circuit, and included between the network N and the filter HP in the usual three-winding transformer for enabling duplex operation between the

transmitting loop TL, the receiving loop RL, and the line.

The printing telegraph apparatus PT is controlled, in receiving, by the line relay LR, and this apparatus comprises the rotary distributor 20, the receiving recorder or printer 21, and suitable synchronizing apparatus indicated at 22 for driving the shaft 23 at a uniform rate and in synchronism with the distributor shaft at the distant station. Arrangements for maintaining distributors of this sort in synchronism are well known in the art and it is not deemed necessary to show or describe the

details of such arrangements for the purposes of the present disclosure. It will be assumed, however, that either the telegraphic signals which actuate the line relay LR or some special control impulses or currents

are transmitted between the station illustrated and the distant station, whereby phase corrections are made in one or both distributors or some other control is exercised to maintain the distributors in step.

The circuit 24 is assumed to lead to a suitable printing telegraph transmitter which may be connected to the line by means of the switch 25 in place of the line relay, if desired.

The alternating current or carrier current channels, as illustrated, comprise the commutators 30, 31, 32 and 33, together with their associated filters. These commutators are indicated as being driven from a common shaft shown in dotted lines and designated as 35. This shaft is assumed to be driven in any suitable manner from the synchronizing apparatus 22 of the printing telegraph equipment and in this manner to

be maintained in synchronism with a corresponding shaft at the distant station, similarly driven from the printing telegraph apparatus at that station, and in turn, driving the commutators employed at that station for the carrier channels.

The channels shown comprise two two-way or full duplex telegraph channels, the two channels of the two-way channel cooperating with the duplex line LL¹ including the commutators 30 and 32, and the channels cooperating with the duplex line LL² including the commutators 31 and 33. The commutator 30, for example, has a pair of its brushes connected by way of the low pass filter LF¹ to the circuit including the contacts of the receiving relay 36 of the line LL¹, this circuit also including a battery. The filter LF¹ is designed to pass frequencies from zero up to the highest essential

frequency involved in the transmission of telegraphic impulses from the relay 36 and suppresses frequencies higher than these. As is well understood, these essential frequencies comprise not only the impulse frequency, but many higher frequencies, due

to the sharp making and breaking of the telegraph circuit to transmit the impulses. The other brushes of the commutator 30 are connected to the common transmitting loop TL by way of the band pass filter TF¹.

Each of the commutators 30 to 33, although indicated as being driven from the same shaft 35, is arranged to operate at a different rate of commutation due to the individual driving connections or to the arrangement of the commutator segments. The commutator 30, for example, may be arranged to operate at a commutating frequency of 150 cycles per second. If then the low pass filter LF¹ transmits frequencies from zero to 100 cycles per second, this range being assumed ample to cover all of the essential frequencies involved in direct-current telegraph transmission, the frequencies resulting from the operation of commutator 30 will include a lower side band having a maximum range from about 50 to 150 cycles and an upper side band comprising a homologous range from about 150 cycles to 250 cycles. The band pass filter TF¹ may, under these conditions, be designed to pass frequencies from 150 to 250 cycles but to suppress the transmission of frequencies both lower and higher than the stated range.

The commutator 31 is arranged to have a different frequency of commutation, for example, 300 cycles per second. The filter LF², through which impulses are received from the relay 37 of the line LL², is assumed to be a duplicate of the filter LF¹. Of the frequencies resulting from the operation of the commutator 31 only the upper side band comprising frequencies from 300 to 400 cycles are transmitted by the band pass filter TF².

The receiving filter RF¹ may be a duplicate of the filter TF¹ and the commutator 32 may be a duplicate of the commutator 30, both of these being operated at the same rate. Similarly, the receiving filter RF² and the commutator 33 may be duplicates of the corresponding transmitting elements. If preferred, however, different frequencies may be used for transmission by the same two-way channel in opposite directions, in which case, the commutators 32 and 33 and the filters RF¹ and RF² would be designed to employ other frequencies. The low pass filters LF³ and LF⁴ included between the respective commutators 32 and 33 and the transmitting relays 39 and 40 may be duplicates of the filter LF¹. Each of the filters above mentioned may be designed in accordance with the principles disclosed in the Campbell patent referred to. While the filters TF¹, TF², etc. have been described as designed to transmit only one side-band, they may if desired be arranged to transmit both side-bands of the respective alternating-current telegraph wave.

The operation of the system is as follows: The printing telegraph channel including the apparatus PT and similar apparatus at the distant station operates in the normal manner and employs frequencies within the range of zero to 120 cycles or less. Currents of these frequencies are transmitted to the line ML and received from the line ML as required, through the filter LP, but currents of these frequencies are prevented from passing into the carrier channel terminals by the high pass filter HP. Currents having frequencies of 150 cycles and higher pass freely through the filter HP, but are prevented from passing into the printing telegraph channel by the filter LP.

Considering now signals originating on the telegraph line LL¹, these signals are received by the relay 36 which actuates its armature to close a circuit including the local battery, the filter LF¹ and a pair of brushes of the commutator 30. This commutator as stated is assumed to have a commutating frequency of 150 cycles and the band pass filter TF¹ to be arranged to pass the upper side band containing frequencies between 150 and 250 cycles. Currents of this range are used exclusively by this channel and are transmitted to the common loop TL and through the three-winding transformer and the filter HP to the main line. In a similar manner, relay 37 is actuated by impulses received over the line LL² and connects battery to the commutator 31, which produces from the direct current impulses, alternating currents having frequency components both lower and higher than the carrier frequency of 300 cycles, while the filter TF² transmits the upper side band including frequencies between 300 and 400 cycles. These currents are also impressed on the loop TL and the line ML. In a similar manner other channels employing commutators having other frequencies and filters of corresponding frequency ranges may be connected with the transmitting loop TL.

The action at the distant receiving station of the currents transmitted to the line ML in the manner described will be clear from considering the action at the terminal illustrated of currents received over the line ML from the distant station. Currents so received having frequencies higher than 150 cycles pass through the filter HP into the common receiving loop RL. Of these currents, those having frequencies within the transmission range of the filter RF¹ pass through this filter to a pair of brushes on the commutator 32. It is assumed that this commutator is a duplicate of the commutator 30 and that a duplicate pair of commutators are employed at the opposite terminal station, one for transmitting and the other for receiving, and further that these commutators are all operated in synchronism. Under these con-

ditions, the filter LF³ and the relay 39 receive direct-current impulses produced by rectification by the commutator 32 from the received alternating-current wave trains, causing relay 39 to actuate its armature and to transmit current from the battery shown to the duplex line LL¹. The filter LF³ serves to smooth out the direct-current impulses by suppressing the high frequency components caused by interruptions or irregularities of operation in the commutator 32. In a similar manner the filter RF² passes currents having another frequency range and the commutator 33 converts the received alternating currents into direct-current impulses for operating relay 40 to repeat into the line LL².

The method of modulation by means of a commutator as above described has certain advantages over the use of the familiar vacuum tube for modulation. The principal advantage of the commutator in the system particularly described herein is that it produces from the applied direct-current impulses the two side frequencies or side bands that are produced by any modulator, but it does not produce certain other frequency components which are found troublesome in the use of vacuum tube modulators. With the arrangements shown herewith in which a direct-current component is applied to the commutator brushes an alternating current of the carrier frequency is also produced in addition to the two side bands and due to sharp interruptions and to unavoidable irregularities in the commutator, there will be a number of frequencies produced all of which are high in comparison with the carrier and side band frequencies. These can easily be suppressed by the use of a filter having a limited transmission range. The commutator does not, however, produce the harmonic frequencies of the applied waves that are to be found in the output of a vacuum tube modulator such as the double, triple, etc., frequency components. If, in place of the commutator 30, for example, a vacuum tube were employed, assuming the impressed telegraph frequencies comprise components from zero to 100 cycles, the double frequencies of all of these components would be produced with an appreciable amplitude. The transmission range of the filter TF¹ is from 150 to 250 cycles and it will be seen that, therefore, the double frequencies of the impressed waves lying between 150 and 200 cycles would also be transmitted by the filter TF¹. Also in this and the other channels the triple and perhaps higher harmonic frequencies would also appear and be transmitted by the channel filters. The effect of these harmonic frequencies is to distort the transmitted wave and cause its form to be less perfect. The effect of a distorted wave of this character

at the receiver is, in a similar manner, to produce false signals or at least to give a less definite rectified impulse by which to actuate the receiving relay. Since, however, these harmonic frequencies are not produced by a commutator the resulting wave form is more accurate and the signals can be reproduced with greater certainty.

In the case of Fig. 1, the main line has been shown as balanced, separate transmitting and receiving commutators for each channel are indicated, and the relays are neutral relays responding to current and no-current conditions of the line respectively.

The invention is equally adapted for use in a system using polarized relays and also there is no necessity of providing in any case separate transmitting and receiving channels conjugately arranged. In systems using polarized relays it is customary to have current of one polarity normally on the line to indicate a space or non-signaling condition. To signal, this current is replaced by impulses of current of the opposite polarity.

Figs. 2 and 3 illustrate the invention as applied to a system using polarized relays. Also the main line is not balanced but each channel contains a single commutating device and a band filter for the channel frequencies, these elements serving for both sending and receiving.

It should be noted that the invention secures the same advantages for multiplex carrier operation which a current-reversing system possesses over a current and no-current system in ordinary telegraph operation. In the current reversing system as usually employed, for a given maximum current flow over the line, the current change is about twice what it would be in a current and no-current system employing the same maximum current flow. If direct current of first one and then the opposite polarity but of the same amplitude is applied to a commutator, a rapidly alternating current is produced having a constant average and also a constant maximum amplitude. However, the effect at the receiver of so reversing the current applied to the commutator is roughly double that of applying impulses of unidirectional current of the same given strength to the commutator alternating with intervals of no current. This will be seen from considering that the alternating current wave produced from a positive impulse immediately following a negative impulse is exactly opposite in phase to the wave produced from the negative impulse. The receiving commutator produces an impulse of one polarity from one such wave and an impulse of opposite polarity from the other wave. It should be noted that a commutator running in synchronism with a received alternating cur-

rent wave transmits every other half wave unchanged and reverses the remaining half waves. The resulting rectified current will then have a positive polarity if the commutator transmits the positive half waves and reverses the negative half waves, and will have a negative polarity if the negative half waves are unchanged but the positive reversed. Obviously, a phase shift equal to one half cycle is all the change that is necessary in the line current to change the received rectified current from one polarity to the opposite. This enables a receiving polarized relay to be actuated directly by current reversals derived as direct-current impulses of opposite sign from received waves. The current change available for operating the relay is substantially double the maximum line current. The maximum alternating current amplitude of the line current remains substantially unchanged, whether signals are being transmitted or only the spacing current.

In Fig. 2, the printing, synchronizing, and the driving devices for the carrier channel commutators correspond to those described in connection with Fig. 1 and are indicated in general at PT². The main line ML² terminates in filters HP² and LP² acting precisely as HP and LP respectively of Fig. 1 to separate the alternating current channel currents as a whole from the printing telegraph impulses. The filter HP² leads to the channel filters BF¹, BF², etc., each of which serves to transmit to and receive from the line the currents of the frequencies utilized by its respective channel. These filters are preferably of the form shown at TF, in Fig. 1, but if the commutators are run at relatively high frequencies, these filters might be replaced by single tuned circuits as might also the filters TF¹, RF¹, etc., of Fig. 1 under similar conditions. Since all three channels shown are or may be identical except for the frequencies which they employ, only the uppermost one in the figure will be described. The commutator 45 as here arranged serves to convert direct-current impulses into alternating current for transmission and also to convert received alternating currents into direct-current impulses for signal reception. These two-way operations of the commutator can take place simultaneously or at different times, as may be desired.

The direct current terminating circuit may have any one of several arrangements. As shown in Fig. 2, a receiving polar relay 46 has its windings included in series with the balancing artificial line or network N which is constructed and proportioned to simulate the actual line to the right of the dotted line a—b. The transmitting batteries 47 and 48 are arranged to be connected under control of relay 50 across the line

and at a point between the windings of relay 46. Relay 46 is balanced therefore with respect to impulses impressed from 47 or 48 and does not respond thereto. Relay 50 is shown controlled from a transmitting terminal circuit L^2 and relay 46 controls a receiving terminal circuit L^1 . A polarized sounder 51 is connected in the circuit L^1 . The circuits L^1 , L^2 may lead as separate lines to any desired distant points, or they may be associated in any of several well-known manners with an outgoing telegraph line (not shown) for duplex or half-duplex operation as may be desired. The various elements are shown in their spacing or non-signaling positions.

In operation relay 50 in responding to spacing current in the circuit L^2 connects battery 48 to the circuit 49 and relay 46 remains unresponsive to this current since the current flows equally and in opposite directions through the two coils of the relay. This current is transmitted through the filter LF^5 , corresponding to filter LF^1 , of Fig. 1, and is applied to the brushes of commutator 45. The action of the commutator is to convert this current into rapidly alternating current of definite frequency which is transmitted to line through the channel filter BF^1 and the high-pass filter HP^2 . An impulse of signaling polarity in the circuit L^2 causes relay 50 to connect battery 47 in place of battery 48 across the line 49 and current of this changed polarity when applied to commutator 45 is converted into alternating current of similar characteristics to that produced when battery 48 is in circuit except that a phase-inversion takes place when current of one polarity in circuit 49 replaces current of opposite polarity as explained above.

In reception current waves of the frequency employed by the channel being described are received from the line ML^2 through filters HP^2 and BF^1 and applied to the terminals of commutator 45. Since as explained in connection with Fig. 1, this commutator is assumed to be operating in synchronism with the received alternating currents, its action is to convert the received currents into direct current, the polarity of which will depend upon whether at the instant when the reversing segments come into functioning the half-wave being received from the line is positive or negative. This, of course, is controlled at the distant transmitter, and as a result of this control as above explained, the rectified currents will consist of both positive and negative impulses which will actuate relay 46 to control the circuit L^1 . The local sounder 51 may be for monitoring purposes.

Instead of the balanced terminal circuit 49 containing network N and balanced relay 46, a simplex circuit as shown in Fig. 3 may

be employed, the line $a-b$ indicating the points of connection of this circuit to the line 49. With switch 52 in the position shown the polarized relay 53 is in condition to receive impulses of reversing polarity 70 from the distant station. It is assumed in the position shown, to be receiving a marking impulse causing the actuation of sounder 54. To transmit, switch 52 is thrown to its upper position and the key is actuated 75 causing reversals of current from the two batteries shown to be applied to the line under control of relay 56. The distant operator can send a break signal by moving his switch 52 to its sending position which 80 will have the effect of reducing the line current to zero for certain intervals and preventing relay 53 from following the movements of the sending operator's key. This arrangement permits the advantages to be 85 gained resulting from the use of current reversals instead of merely makes and breaks.

In Fig. 1, the relay 36 might obviously be made to control application of current of alternate polarities in the same way as relay 56 of Fig. 3, the relay 53 being omitted from the circuit in such a case. Relay 39 and each of the other receiving relays could then be replaced by a polar relay such as 53 if desired.

It is to be understood that the invention is not limited to the actual circuit arrangements shown or described but that it is capable of various modifications and its separate features are capable of general application 100 Its scope will be defined in the claims.

What is claimed is:

1. The method of telegraphy comprising subdividing direct current telegraph impulses and reversing the alternate subdivided portions to convert said current impulses into alternating current of definite frequency, transmitting said alternating current and reversing alternate portions of transmitted alternating current at a synchronous rate to reproduce said current impulses. 110

2. The method of telegraphy comprising subdividing direct current telegraph impulses and reversing the alternate subdivided portions to convert said current impulses into alternating current of definite frequency, selectively transmitting said alternating current to a distance, selectively receiving said alternating current and synchronously reversing the alternate portion 120 of the received current to reproduce said direct-current impulses. 115

3. The method of multiplex telegraphy which comprises subdividing a plurality of telegraph direct current impulses representing respective messages and reversing the alternate subdivided portions at respectively different rates to produce alternating currents of respectively different frequencies, simultaneously transmitting the said alter- 130

nating currents of different frequencies over the same path and selectively receiving the message currents in accordance with the frequencies of the transmitted currents.

5. 4. The method of multiplex telegraphy comprising subdividing each of a plurality of direct-current message currents and reversing the alternate subdivided portions of said currents at respectively different rates 10 and simultaneously selectively transmitting the commutated currents over the same path.

5. The method of multiplex telegraphy which comprises transmitting current impulses representing certain telegraphic messages directly to line, commutating current impulses representing other telegraphic messages to convert said impulses into alternating currents of frequencies higher than the frequencies of said current impulses, 15 transmitting said alternating currents to line, separating said high frequency currents from said transmitted current impulses by filtering, receiving said transmitted impulses directly from the line and commutating said 20 high frequency currents to convert them into telegraphic current impulses for message reception.

6. In a telegraph system, a main line, terminal telegraph circuits carrying direct current message impulses, and current reversing commutators for converting said direct current message impulses into alternating currents of different frequencies for transmission over said line.

35. 7. In a telegraph system, a main line, terminal telegraph circuits, current reversing commutators connected between said terminal telegraph circuits and said line, and frequency selective circuits connected between said commutators and said line.

40. 8. In a telegraph system, a line, means to transmit alternating currents thereover in accordance with telegraph signals, a direct current terminal telegraph circuit and a current reversing commutator operated in synchronism with said alternating currents for converting said alternating currents into direct current message impulses and impressing the direct current impulses on said terminal telegraph circuit.

55. 9. In a telegraph system, a main line having stations, a direct current terminal telegraph circuit at each of two stations on said line, synchronously operating current reversing commutators, one at each of said stations connected between the main line and a said terminal telegraph circuit, one of said commutators serving to convert direct current telegraph impulses into alternating currents for transmission over said line and the other commutator serving to convert received alternating currents into direct current telegraph impulses for the associated terminal circuit.

60. 10. In a multiplex telegraph system, a

main line, two or more direct current terminal telegraph circuits at the same terminal of said line, an individual current reversing commutator connected between each terminal circuit and said line for converting direct current telegraph impulses in said terminal circuits into alternating currents for transmission over said line, said commutators each having a different rate of commutations, whereby the several alternating currents so produced have different frequencies.

70. 11. In a multiplex telegraph system, a main line, means to transmit simultaneously thereover alternating currents of different frequency representing separate messages, two or more direct current terminal circuits at the same terminal of said line, a commutator for each said terminal circuit, each commutator arranged to operate in synchronism with a different one of said alternating current transmissions for converting the corresponding alternating current into direct current impulses for the associated terminal circuit.

80. 12. In a multiplex telegraph system, a main line having stations, a plurality of direct current terminal telegraph circuits at each station, a separate commutator between each of the terminal circuits at one station and said line having respectively different rates of current commutation for converting the direct current impulses in each of the associated terminal telegraph circuits into alternating currents of as many different frequencies for transmission over said line, commutators at the other station connected between said line and the respective terminal telegraph circuits, each one of said last-mentioned commutators operating in synchronism with a different respective commutator at the first-mentioned station for converting the received alternating currents of the different frequencies into direct current telegraph impulses for the several associated terminal circuits and selective circuits connected between each of said commutators and the line for distinguishing between the frequencies employed by the several commutators.

90. 13. In a multiplex telegraph system, a line, a printing telegraph channel including a rotary distributor, an alternating current telegraph channel including a rotating current reversing commutator for converting telegraphic current message impulses into alternating currents for transmission and a common driving means for said rotary distributor and said rotating commutator.

100. 14. In a multiplex telegraph system, a line, means to transmit telegraphic current impulses thereover, means to transmit also alternating currents thereover having frequencies higher than said current impulses,

said last mentioned means comprising a current reversing commutator for converting telegraph current impulses into alternating current and a filter between said commutator and said line for transmitting said alternating currents and for excluding from the commutator circuit the telegraphic impulses on said line.

15. A composite telegraph system, comprising a line, a printing telegraph channel arranged to transmit thereover including synchronized transmitting and receiving rotary distributors at respective terminals of said line, and a plurality of carrier current channels also arranged to transmit over said line, each channel including commutators at each terminal, all of said commutators and said rotary distributors at the same terminal having common driving 20 means.

16. In a telegraph system, a main line for transmitting alternating current telegraph signals, a transmitting and a receiving branch for said line at the same station, 25 a transmitting direct current terminal circuit, a receiving direct current terminal circuit, a current reversing commutator connected between the transmitting circuit and the transmitting branch for converting direct current message impulses in said transmitting terminal circuit into alternating current for transmission over said line and a current reversing commutator connected 30 between said receiving branch and said receiving terminal circuit for converting alternating currents received over said line into direct current for said receiving terminal circuit.

17. A system according to claim 16 having a selective circuit connected between each of said commutators and the respective transmitting or receiving branch of said line.

18. In a carrier telegraph system, a current reversing commutator device for converting the energy of the received carrier waves into direct current energy, an output circuit for said device, a polarized relay having its winding connected in the said circuit, said device being arranged to produce direct current flow in either direction through said windings to actuate said relay in the corresponding direction.

19. In a carrier telegraph system, a sending station, a distant receiving station, means at the sending station to produce direct current impulses of opposite polarities, means to transmit the energy of said impulses to the receiving station in the form of carrier current waves, means at the receiving station for converting said carrier current into direct current impulses and a polarized relay arranged to be actuated in opposite directions by the energy of the converted impulses.

20. In a carrier telegraph system, a sending circuit having means to produce therein, code impulses of positive and negative current, a translating circuit for converting said impulses into carrier current, a receiving translating circuit for converting said carrier current into code impulses and a polar relay arranged to actuate its armature in opposite directions in response to said received impulses, the only source of current 70 employed being in said sending circuit.

21. In a multiplex carrier telegraph system, a line having stations, a plurality of selective circuits for passing each a different frequency connected to said line at the same 80 station, a current reversing commutator connected to each selective circuit on the opposite side from said line connection, said commutators being arranged to have respective rates of current alternation within the transmission range of the associated selective circuit and terminal telegraph circuits connected to said commutators.

22. A two-way translating circuit for carrier telegraph line comprising a selective 90 circuit for receiving alternating current from the line and transmitting alternating current to the line, a direct current telegraph circuit, and a commutator connected between said telegraph circuit and said selective circuit for converting direct current telegraph impulses into alternating current for the line and alternating current received from the line into direct current telegraph 95 impulses.

23. A two-way carrier telegraph channel comprising at each of two stations a single current reversing commutator, said commutators operating in synchronism and each serving to convert direct current telegraph 100 impulses into alternating current and alternating current into direct current.

24. A two-way translating device for an alternating or carrier current channel for converting direct current telegraph impulses 110 into carrier current impulses and carrier current impulses into direct current impulses comprising a current reversing commutator operating in synchronism with the carrier current alternations.

25. In a carrier telegraph system, a current reversing commutator running at a definite commutating frequency, a direct current telegraph circuit, sources of current of opposite polarities in said circuit, a high 120 frequency line, said commutator arranged to convert message current of each polarity in said telegraph circuit into alternating current for transmission over said high frequency line.

26. In a carrier telegraph system, a direct current telegraph circuit, an alternating current line, a current reversing commutator between said circuit and said line, means to impress direct current message impulses 130

from said telegraph circuit on to said commutator to produce alternating current for transmission over said line, and means to impress on said commutator alternating currents received from said line to produce direct current message impulses for transmission over said telegraph circuit.

27. A two-way repeating circuit for use between a direct current line and a high frequency line, comprising a current reversing commutator arranged to convert direct current telegraph impulses into alternating current telegraph impulses and alternating current telegraph impulses into direct current telegraph impulses.

28. In a carrier telegraph system, means comprising a current-reversing commutator to convert energy of direct current telegraph impulses into the energy of alternating current and means comprising a current-reversing commutator to reconvert said energy of alternating current into direct current telegraph impulses.

29. In a carrier telegraph system, means comprising a current-reversing commutator to convert energy of direct current telegraph impulses of one polarity into the energy of alternating current, and to convert

the energy of direct current telegraph impulses of opposite polarity into the energy of alternating current of opposite phase from said first-mentioned alternating current, means comprising a current-reversing commutator to reconvert said first-mentioned alternating current energy into direct current energy of one polarity and to reconvert said alternating current energy of opposite phase into direct current energy of opposite polarity from said last mentioned direct current energy.

30. The method of telegraphy comprising subdividing direct current telegraph impulses of respectively opposite polarity and reversing the alternate subdivided portions to produce alternating currents of respectively opposite phase, and at a receiving point reversing alternate portions of said alternating currents to reconvert said alternating currents of respectively opposite phase into direct current impulses of respectively opposite polarity.

In witness whereof, I hereunto subscribe my name this 28th day of February A. D., 1922.

RALPH V. L. HARTLEY.
